UNITED STATES PATENT OFFICE

160,878

RECORD PLAYER

Otto Rudolph Nemeth, Los Angeles, Calif.

Application January 17, 1950, Serial No. 7,293

Term of patent 7 years

(CL. D56—4)

To all whom it may concern:

Be it known that I, Otto Rudolph Nemeth, a citizen of the United States, residing in Los Angeles, in the county of Los Angeles and State of California, have invented a new, original, and ornamental Design for a Record Player, of which the following is a specification, reference being had to the accompanying drawing, forming part hereof:

I claim:

The ornamental design for a record player, as shown.

OTTO RUDOLPH NEMETH.
